UNITED STATES PATENT OFFICE

FRED SIEMEN AND FRANK P. LEVINE, OF LOS ANGELES, CALIFORNIA

GARMENT HANGER

Application filed August 5, 1930. Serial No. 473,143.

This invention relates to improvements in garment hangers.

The general object of the invention is to provide an improved hanger which is adapted to support a garment at the shoulders and retain it in an extended position below the shoulders.

Another object of the invention is to provide a novel garment hanger including means whereby the hanger may be used as an easel to display the garment.

Other objects and the advantages of this invention will be apparent from the following description taken in connection with the accompanying drawings wherein:

Fig. 1 is a perspective view of our improved garment hanger showing it in a position to be used as an easel.

Fig. 2 is an enlarged fragmentary perspective view of a portion of the hanger shown in Fig. 1.

Fig. 3 is a perspective view of a modified form of hanger.

Fig. 4 is an enlarged fragmentary section of a portion of the hanger shown in Fig. 3 and

Fig. 5 is an enlarged fragmentary view of a hanger showing a modified hook construction.

Referring to the drawing by reference characters we have indicated our improved garment hanger generally at 10. As shown the device is made of steel or other wire and includes a body portion 11, a hanging hook 12, and an easel portion 13.

The body portion 11 is preferably formed of a single length of wire bent to form a triangular lower portion 14, 15 and 16, and an upper polygonal portion 17, the opposite ends of which are of less length than the top and bottom portions.

The wire meets at the apex of the triangle portion and it is secured there as by spot welding indicated at 18 while the free ends 45 of the wire are bent to form loops 19.

The loops 19 are positioned one above the other and a straight shank portion 20 of the hook 12 is positioned in the loops and provided with enlarged protuberances 21 above 50 and below the loops. These protuberances

may be formed of solder or some similar material or may be integral with the wire. The shank 20 is free to rotate in the loops 19 and the protuberances retain the shank in position in the loops.

The easel 13 is preferably made of a single length of wire 23 which is bent to form a straight base 24 and angular side members 25 which are crossed as at 26 and the free ends of which are provided with loops 27 which surround the upper members of the hexagonal portions 17 of the body and are positioned one on each side of the loops 19.

When a garment such as a dress is positioned on the device 10 the shoulders of the dress are positioned on the polygonal portion 17 and the triangular portions retain the lower portion of the dress in an extended position.

When the hanger is used only for supporting the dress in a hanging position the easel portion may be folded against the body portion and the dress placed over the easel portion.

When it is desired to use the easel portion 13 for supporting the device 10 the easel portion is slipped through the neck of the dress first so that it will be on the outside when the dress is correctly positioned on the device.

In Figs. 3 and 4 we have shown the device 10 without the easel portion 13 secured thereto. To support the device in a standing position when the device does not include the easel portion 14 we provide a rod 30 which is pointed at one end as at 31. The pointed end of the rod 30 is inserted in one of the loops 19 and wedged against the shank 20 of the hook 13 as clearly shown in Fig. 4. The friction of the parts retain it in this position.

In Fig. 5 we have shown a modified hanging hook which is indicated at 33. As shown one of the free ends of the wire indicated at 17' beyond the polygonal portion 17 is provided with a loop 34 and the other end portion of the wire is bent at an angle and is positioned in the loop 34 and then bent into shape to form the hook 33.

From the foregoing description it will be apparent that we have provided a novel gar-

ment supporting device which is simple in construction and highly efficient in use.

Having thus described our invention, we claim:

- 5 1. In a garment support including a body portion and a hanging hook, said body being made of a single length of wire and including a triangular portion and a hexagonal portion thereabove, the opposite ends of said 10 hexagonal portion being of less length than the top and bottom members of said hexagonal portion, a loop on each end of said wire, said loops being superimposed, said hook including a shank, said shank being positioned in said loops and rotatable therein and a protuberance on said shank above and below said loops.
- 20 2. A garment support including a body portion and a hanging hook, said body being made of wire and including a triangular portion and a polygonal portion thereabove, the opposite ends of said polygonal portion being of less length than the top and bottom members of said polygonal portion, a loop on 25 the ends of said wire, said loops being superimposed, said hook including a shank, said shank being positioned in said loops and rotatable therein and a protuberance on said shank above and below said loops.
- 30 3. In a garment support including a body portion, a hanging hook and a brace member, said body being made of a single length of wire and including a triangular portion and a polygonal portion thereabove, the two sections of said wire forming said triangle being secured together at the apex of said triangle, the opposite ends of said polygonal portion being made of less length than the top and bottom members of said polygonal 35 portion, means whereby said hook connects the free ends of said body wire, said brace member being made from a single length of wire and including a base portion, the free ends of said brace wire being formed into 40 loops surrounding the wire forming the top of said polygonal portion, one on each side of said loops of said polygonal portion.
- 45 4. A garment support including a body portion, a hanging hook and a brace member, said body being made of wire and including a triangular portion and a polygonal portion thereabove, the opposite ends of said polygonal portion being of less length than the top and bottom members of said polygonal portion, a loop on each end of said wire, said loops being superimposed, said hook including a shank, said shank being positioned in 50 said loops and rotatable therein, a protuberance on said shank above and below said loops, said brace member being made from a single length of wire and including a base portion, the ends of said brace wire being formed into loops and surrounding the wire forming the top of said polygonal portion 55 one on each side of said loops.

5. A garment hanger including a body portion, a hanging hook and a brace member, said body being made of a single length of wire and including a triangular portion and a polygonal portion thereabove, means to prevent the side members of said triangular portion from moving away from each other, means whereby said hook connects the ends of said body wires, said brace member being made of a single length of wire and including a base portion, and means to hingedly connect said brace member to said polygonal section.

In testimony whereof, we hereunto affix our signatures.

FRED SIEMEN.
FRANK P. LEVINE.
